UNITED STATES PATENT OFFICE.

NELON P. DAVIS, OF TERRY, MISSISSIPPI.

OIL-BAFFLE PLATE.

Application filed March 26, 1921. Serial No. 455,871.

To all whom it may concern:

Be it known that I, NELON P. DAVIS, a citizen of the United States, residing at Terry, in the county of Hinds, State of Mississippi, have invented certain new and useful Improvements in Oil-Baffle Plates; and I do hereby declare the following to be a full, clear, and exact description of the invention, such as will enable others skilled 10 in the art to which it appertains to make and use the same.

This invention relates to oil baffle devices to be used in connection with internal combustion or other engines employing the 15 splash system of lubrication, the primary object of the invention being to provide means of simplified and improved nature for preventing an excess of oil being thrown from the crank case to the engine cylinders, 20 yet permitting of sufficient oil being distributed to the latter to insure thorough and proper lubrication.

A further and particular object of the invention is to provide baffle plates for use 25 in connection with the motor for the purposes specified, which are of extremely simple construction and of inexpensive manufacture, which may be readily applied to engines now in use without alteration or 30 change in any of the construction of the latter; which are adaptable to engines of various types, which are of such construction as to be formed and properly fitted to 35 irregularities in each engine casing, and which may be readily applied to the motor of any ordinary mechanism.

With these objects in view, together with others which will appear as the description 40 proceeds, the invention resides in the novel construction, combination and arrangement of parts, all as will be described more fully hereinafter, illustrated in the drawings, and particularly pointed out in the claims.

In the drawings:

45 Figure 1 is a vertical transverse sectional view taken through an engine of conventional design and illustrating the application thereto of a baffle plate embodying the invention.

50 Figure 2 is a fragmentary sectional view taken horizontally through a part of the engine casing and illustrating the baffle plate in plan.

55 Figure 3 is a detail perspective view of one of the baffle plates.

Figure 4 is a fragmentary sectional view

taken vertically through a portion of a conventional engine and showing certain wings of the baffle plate bent upwardly and away from the cam shaft.

60

Figure 5 is a fragmentary sectional detail view on the line 5—5 of Figure 2.

Referring now more particularly to the drawing, 5 indicates generally the casing of the engine, the latter in the present instance 65 being an internal combustion motor, but it will be understood that the device of my invention is not necessarily limited to use in connection with such motors as it may be very effectively employed with other types 70 of engines and power plants. This casing includes the cylinder portion 6 containing piston 7, the latter being connected by pitman 8 with an arm of crank shaft 9, disposed within the crank case of the motor, 75 all as will be readily understood. As the motor operates, the oil in the well at the bottom of crank case is thrown or splashed upwardly so as to lubricate the pistons and cylinders, cam shaft 10 and other movable 80 parts enclosed by the casing, and it very often happens that the oil thus splashed is too freely distributed within the casing, whereby excess amounts of oil are permitted to enter the combustion chamber of the cylinder and thereby impede the power of the engine and foul the spark plugs. The device of my invention includes a baffle plate or plates disposed between the pistons of the engine and the crank shaft, to intercept 85 an appreciable quantity of the oil splashed by the cranks and deflect such oil back into the oil well, thus overcoming the possibility of the cylinders becoming fouled with lubricating oil.

95

The baffle plates of my invention comprise base or body portions indicated at 11, formed preferably of a substantially heavy rigid metal, one end of the plate being down-turned or offset, as at 12, to receive retaining screws or bolts 13 for rigidly securing the base to one of the inner walls of the engine casing. In the present instance, the base portion 11 is secured to that side of the casing opposite to the cam shaft, and the said member 11 is provided with transversely disposed slots or notches 14 spaced apart proper distances to receive and loosely accommodate the pitmen connecting the pistons with the cranks of crank shaft 9. The 100 slots or notches 14 will, of course, be spaced apart proper distances in order that a re-

cess may be provided for each of the pitmen of the engine. The base or body 11 may be made in one continuous strip, if desired, extending longitudinally throughout 5 the length of the engine casing, or the body may be made in two or more sections, all of similar construction, and fitted together and bolted within the casing so as to have the appearance and function of one continuous 10 base. It will be observed that the width of the base plate is such that the free ends thereof terminate an appreciable distance inwardly from the cam shaft and its associated mechanism.

15 Projecting inwardly into each of the slots or notches 14 of the base or body and outwardly from the free end of the latter are deflector members indicated at 15. These deflector members are made of flexible material, 20 such as thin tin, and project into the slots 14 a comparatively short distance. The deflector members 15 at the free edges of the plate are of such length as to extend approximately to the wall of the engine casing opposite to which the base members 11 are bolted and the said end deflectors or baffles, indicated at 16, are of such width as to meet at their adjacent edges, as shown. By constructing the deflector portions of the baffles 25 in the manner specified, it is obvious that they may be shaped so as to closely fit with projections or other irregularities in the engine casing or about any of the movable parts of the motor, certain portions of the deflectors being cut or slotted as at 17 to facilitate 30 the bending and fitting operation. The baffle members defining the slots 14 are to be bent downwardly in the general direction of the crank case, and have their free edges disposed so as to comfortably clear the pitmen 8, allowing free unimpeded movement 35 of the latter and yet lying close to the sides of the same. The end deflectors 16 are shaped so as to engage or substantially engage 40 with the remote wall of the engine casing, and as the lateral edges of these deflector members meet each other it is obvious that great quantities of oil will be prevented being thrown to the upper part of the casing. 45 At the outer ends of the base or body members 11, baffle fingers or plates 18 are provided, the same being flexible or pliable to adapt themselves to any irregularities in the end walls of the engine casing. The 50 flexible deflector members may be formed of any suitable pliable material, such, as has been heretofore stated, as thin tin, and these deflector members may be made in any number of pieces or sections as desired. It may 55 be found expedient, however, to construct these baffle members all in one piece, as by stamping, and then securing the same upon the base or body members 11. The inner ends of the metal plates constituting the deflectors, will constitute a connector for the 60 65

various portions, and the body of the deflector members may be secured to the base 11 by means of rivets 20.

By constructing the baffle members in the manner specified, the base members 11 will 70 possess sufficient rigidity to properly support the flexible baffle or deflector elements, and the latter may be so shaped as to provide substantially a partition wall between the crank case and the lower portion of the engine cylinders, sufficient room being left or 75 provided for the free unimpeded operation of the movable parts of the engine. The downturned edges of the deflectors 15 will catch the oil thrown upwardly by the cranks, 80 and will direct it down into the oil well. The end deflector 16 will prevent oil being thrown against the cam shaft and gaining access to the engine cylinders, while the said cam shaft will receive sufficient lubrication from the 85 drip of the engine cylinders. Should it be found that the flexible deflector members too snugly accommodate the movable parts, thus preventing proper lubrication of the engine parts, they may be bent or deflected backwards 90 so as to allow more space for the lubricant to pass.

By the use of a baffle device so constructed, it is obvious that the oil pressure in the lubricating system of the engine may be raised 95 appreciably, to insure proper lubrication of all of the bearings, and yet such increased pressure will not increase the amount of lubricant delivered to the pistons and cylinders. By thus limiting the amount of oil supplied 100 to the cylinders and pistons, it is apparent that leakage of the oil past the piston rings and into the upper portions of the cylinders, in excessive quantities, will be precluded, whereby fouling of the cylinders and the 105 spark plugs, and accumulations of excess oil upon the piston heads will be overcome.

While the above is a description of the invention in its preferred form, it will be understood that the invention is not to be limited thereto, as various changes in the minor details of construction and arrangement of parts may be resorted to without departing from the spirit of the invention as defined by the claims.

115 What is claimed is:

1. In a baffle device for engines, a base plate formed of substantially rigid material and having an attaching flange along one edge, and being transversely slotted, a sheet 120 of flexible material carried by said plate and being transversely slotted in registry with the slotted portion of the base plate, the walls of the slots of said sheet being formed with angularly extending deflector blades 125 projecting into the slots of the base plate, the said sheet projecting beyond certain edges of said base plate and being extended angularly.

130 2. As an article of manufacture, a baffle

for engines comprising a sheet metal plate body having an angularly extended attaching flange on one edge, the remaining edges of the sheet being extended at obtuse angles, 5 the body being formed with transverse slots with angularly extended blades along the longer walls thereof.

In testimony whereof, I affix my signature, in the presence of two witnesses.

NELON P. DAVIS.
